[57] **CLAIM**

The ornamental design for a long-term blood pressure measuring instrument to measure the blood pressure of a human being, as shown and described.

DESCRIPTION

FIG. 1 is a perspective view of a long-term blood pressure measuring instrument, showing my new design;

FIG. 2 is a side elevational view thereof, with the opposite side being identical to that shown except for the battery compartment cover which is not present on the opposite side;

FIG. 3 is a right end elevational view thereof;

FIG. 4 is a left end elevational view thereof;

FIG. 5 is a top view thereof; and,

FIG. 6 is a bottom view thereof.
